H. C. CALDWELL

REGULATING BURNER CAP

Filed Aug. 31, 1922

INVENTOR
Henry C. Caldwell
By J. W. Ellis
ATTORNEY

UNITED STATES PATENT OFFICE.

HENRY C. CALDWELL, OF BUFFALO, NEW YORK.

REGULATING BURNER CAP.

Application filed August 31, 1922. Serial No. 585,402.

To all whom it may concern:

Be it known that I, HENRY C. CALDWELL, a citizen of the United States of America, and a resident of the city of Buffalo, county 5 of Erie, and State of New York, have invented certain new and useful Improvements in Regulating Burner Caps, of which the following is a full, clear and exact description.

10 My invention relates generally to means for and process of burning gas, and more particularly to such means and process, whereby the height of the flame may be adjusted and maintained at a predetermined 15 distance above the burner, irrespective of the gas pressure or velocity.

It is well known to those skilled in the art, that the ordinary gas burner is so located that the cooking utensil will be disposed at the most efficient point when the burner is working under normal conditions. When, however, the gas pressure is low, the velocity of the gas mixture will also be low, and the flame on such a burner will not 25 reach the cooking utensil under these conditions, and the already poor efficiency in such a burner will drop very materially.

The principal object of my invention has been to overcome the disadvantages above 30 enumerated, and to provide a burner which is not only very efficient under normal conditions, but one which will also efficiently burn gas when at a lower pressure.

Another object has been to provide a burner 35 so arranged that a number of the burner openings may be covered or uncovered to suit the gas pressure and velocity, whereby the size or lateral dimensions of the flame may be governed in accordance with the 40 pressure and velocity so as to bring the flame height to the desired predetermined distance.

Another object has been to provide a gas burner, having comparatively large orifices, 45 whereby all kinds of gas may be burned without any change.

Furthermore, the orifices are in the form 50 of passageways of sufficient length so as to prevent back-firing when a very rich gas is used, or when the gas pressure is low.

Moreover, my burner is of such a nature 55 that all parts are easily disassembled and made accessible for thorough cleaning.

The above objects and advantages have 55 been accomplished by the device shown in the accompanying drawings, and by the

process which may be carried out by such a device. In the drawings:

Fig. 1 is a plan view of my complete burner, partly in sections. 60

Fig. 2 is a side, sectional elevation of the same.

Fig. 3 is a fragmentary, plan view showing a modified form of invention.

Fig. 4 is a fragmentary, plan view of another modified form of invention. 65

Fig. 5 is a fragmentary, sectional elevation of the modification shown in Fig. 4.

Referring to Figs. 1 and 2, the burner comprises a base 10, provided with a mixer 70

tube 11, at the outer end of which is formed a mixer 12. At the end of the mixer 12 is the customary air regulator 13, comprising preferably two plates as shown, which may be relatively rotated to increase or decrease 75 the air openings in the well known manner. Arranged at the center of the air regulator is a gas cock 20. The upper surface 14 of the burner is preferably flat, in the face of which is provided a number of recesses 15. 80 Each of these recesses is bounded on one side by a radial surface 16 and on the other side preferably by a series of steps 17. The base is provided in its center with a well 18, which has an opening 19 at its upper end. 85 This opening is in communication with the series of recesses 15, whereby the combustible mixture is supplied to the recesses.

Arranged over the base 10, and rotatable thereon, is a muffle 25, which is preferably 90 provided with a downwardly extending annular flange 26 at its outer edge, for engagement with the upper edge of the base, whereby the muffle will be kept in position and yet permit its being rotated. The muffle 95 is provided with a series of upstanding ridges 27. These ridges are arranged preferably in a radial manner, and a series of apertures or passageways 28 is formed in each of them. These apertures are relatively 100 larger than those usually provided in gas burners and thus it is possible to use my burner on any of the different kinds of gas. Even though the apertures are large, the length of the passageways is such that all 105 back-firing is prevented.

The passageways are preferably spaced at such a distance from each other that the outer row of them will register with the steps 17 bounding one side of each of the recesses 15 110 in the base. When the muffle is placed upon the burner base and the radial series of

passageways is brought in register with that part of each recess 15, which lies adjacent the radial side 16 thereon, all of the passageways 27 of the muffle will be opened, and 5 gas will be allowed to pass through all of them. When, however, the muffle is rotated in a clockwise direction, one, two, three, four, or more of the passageways may be closed by the engagement of the flat top 10 14 of the base with the bottoms of such apertures.

In the modified form of the invention shown in Fig. 3, the recesses 30 are bounded on one side by a straight radial surface 31 15 and on the other side by a straight angularly arranged surface 32. In this form of invention, some of the apertures will be only partially closed by the rotation of the muffle 25, while others will be fully closed, depending 20 upon the amount of rotation of the muffle. If the muffle is rotated so that the radial series of passageways are in register with the flat surfaces 33, all of the apertures covered by such surfaces will be fully closed.

25 In the modified form shown in Figs. 4 and 5, 35 is the base of the burner, and 36 the muffle. The muffle is arranged over the base, as in the other forms, but is not rotatable therewith. The recesses in the base are 30 omitted and a disc 37 is arranged preferably between the base and the muffle. This disc is provided with a handle 38, which extends through a slot 39 formed in the flange of the muffle. In this form of device, the disc is 35 provided with a series of recesses 40, bounded on one side preferably by a radial surface 41 and on the other side preferably by means of the stepped surface 42. If desired the stepped surface may be omitted, and the 40 angularly arranged surface of the form shown in Fig. 3 employed. In this form of the invention, the apertures or passageways of the muffle 36 are controlled by an oscillation of the disc 37.

45 In carrying out my process by means of the apparatus herein shown and described, the gas is turned on at the gas cock 20, the air openings having been previously adjusted so as to give maximum results with 50 the gas being used under its normal pressure. The gas and air are then mixed in the mixer 12 and are conducted through the mixer tube 11 into the well 18. From the well the gas mixture is conducted to the series of radial 55 recesses 15 whence it passes into and through the registering apertures or passageways 28. Of course, the passageways, which lie over the well 18 are always supplied with gas,

irrespective of the position of the muffle. The muffle is now adjusted to either increase 60 or decrease the number of passageways 28, through which the gas mixture passes, whereby the height of the flame may be controlled. It will be seen that by means of a 65 rotatable muffle, substantially one-half of the passageways 28 may be cut off or closed, thus confining the flame area to the center of the burner, and, of course, increasing its height. This is, of course, only needed when 70 the gas pressure is so low that the flame will not reach the height at which most efficient heating results, but by reducing the number of apertures, the height of the flame may be easily controlled and brought to the pre-determined point.

75 While I have shown and described a number of forms of apparatus by which my process may be carried out, it is obvious that detailed modifications may be made in the apparatus, and that the process may be carried out by other forms than those shown and described; and I do not, therefore, wish to be limited to the exact embodiments herein shown and described.

Having thus described my invention, what 85 I claim is:

1. A gas burner comprising a base portion, and a muffle, the base portion being formed with a flat top and provided with radially arranged recesses, each recess being of varying width, whereby a number of 90 passageways in the muffle may be closed by the oscillation thereof.

2. A gas burner comprising a base portion 95 having a series of radial recesses at its upper face, such recesses being so formed as to have varying widths throughout their lengths, and a muffle, the muffle being rotatable and provided with a series of concentrically and radially arranged passageways so that a predetermined number of such passageways may be registered with the recesses.

100 3. A gas burner comprising a base portion having a series of radial recesses at its upper face, such recesses being so formed as to have varying widths throughout their lengths, and a muffle, the muffle being rotatable and provided with a series of comparatively long concentrically and radially arranged passageways so that a predetermined number of such passageways may be registered with the recesses.

105 In testimony whereof, I have hereunto signed my name.

HENRY C. CALDWELL.
